GAME APPARATUS

Thomas F. McLaughlin, Boston, Mass.

Application October 26, 1937, Serial No. 171,039

7 Claims. (Cl. 273—25)

My present invention relates to game apparatus and athletic equipment and aims to provide means for improving the visibility of important stations or areas in the play of games, especially, for example, the home-base area or home-plate of a baseball diamond.

In the drawing, illustrating by way of example one embodiment of the invention;

Fig. 1 represents a device illustrative of the invention as installed in association with the home-base region of a baseball playing field or diamond;

Fig. 2 is an enlarged vertical section on the line 2—2 of Fig. 1;

Fig. 3 is a further enlarged detail sectional view corresponding to a portion of Fig. 2; and

Fig. 4 shows a home-plate element or unit comprised in the apparatus of the invention, for use interchangeably with the corresponding unit seen in Figs. 1 and 2.

Referring first to Fig. 1, a home-plate structure in accordance with my present invention is there shown in its operative or playing position as on a baseball field or diamond, said structure as a whole being indicated by the numeral 5. In said Fig. 1 portions of the first base and third base lines of the diamond are represented at A and B respectively, and the righthand and lefthand batters' boxes are indicated by the rectangular areas R and L. The home-plate is located in the usual manner at the home-base station, in the internal angle at the juncture of the base lines. The exposed or surface portion of my home-plate structure preferably and as illustrated is of regulation size and shape, having the pentagonal form as seen in Fig. 1.

The plate structure of the invention as herein illustrated, and referring first to the parts as seen in Figs. 1 and 2, includes a main plate member 7 of a durable resilient material such as rubber or a rubber or other composition. This plate member or element is afforded adequate rigidity as a whole, being, in the example shown, provided with or secured flatwise on a rigid support or platform 9.

Operatively associated, or structurally incorporated, with the home-plate member or element 7, in the manner of a frame or border for it in the illustrated example, and in the same plane with it, I provide translucent means 11. Said means, as shown for the purposes of illustration, may be in the form of a continuous annular strip-like member enclosing the resilient plate member 7 or may comprise a number of sections disposed along the edge portions of the plate member 7 so

as to present with the latter an exposed horizontal playing surface of the desired shape and dimensions. In the form shown this translucent means or element 11 includes an outer and vertically unobstructed portion having an exposed upper face as at 12, and an inner or securing portion or flange 13 adapted for attachment to the support 9, as by means of screws or the like 14. Said securing portion 13 may be of less height than the outer or light-transmitting portion, to provide a shoulder for underlying reception of the edge portions of the plate member 7, in the manner seen in Fig. 2.

The translucent means 11 as a whole or at least the outer and vertically unobstructed portion below the face 12 thereof is composed of a durable, nonbreakable material having the capacity for transmitting light without glare effects, and being such that an adjacent light source will afford to the material a soft diffused but clearly 20 distinct illumination, with a similar effect as by a heavily frosted glass, so that the material will present a luminous or glowing area clearly defined by the margins of the material itself. Various plastic or other substances such as those 25 having a cellulosic base, phenol derivatives, and others, may be employed for the purpose. Among materials which I have found particularly satisfactory in this connection are those known commercially as lucite, catalin, and others of a like 30 nature. The width or lateral extent of this translucent means may be variously proportioned within the defined playing area of the plate element as a whole and, particularly if said translucent means is itself of a resilient character, may be 35 largely or wholly coextensive with said area, so long as the transmitted light is diffused and without objectionable glare effects, as stated.

By non-breakable I imply that the material should be capable of withstanding the ordinary 40 usage to which a home-plate is subjected in play, without undue chipping, cracking or other objectionable deformation.

In the illustrated construction, the resilient plate 7, the translucent means 11 and the support 9 for said parts comprise a structural unit adapted readily to be placed in or removed from operative position for use in the play of a game. This unit may further include depending means such as the foot or post 15 located inwardly of 50 the translucent border 11 and secured to the platform 9 in any convenient manner. Where a metal construction is used, the attachment may be by welding, as indicated at 16.

For receiving and supporting this unit I have 55

herein provided a base, casing or shell 20 adapted to be set or built into the ground G at the home-base location, substantially flush with or slightly below the adjacent playing surface. This casing 5 or base 20 may be formed of any suitable material such as metal, cement, wood or composition and may be constructed on the site or otherwise, the material in any case preferably being treated or being of an inherent character to resist moisture 10 and other outdoor and underground conditions.

The casing 20 provides within it a chamber or compartment 21 having means for removably receiving and positioning the plate unit above referred to. In the form shown the post 15 is 15 adapted to be firmly held in fixed position as by means of a sleeve or the like receiving formation 22 integrally or otherwise connected to the casing 20, for example, at the bottom of the latter, as indicated at 23.

20 To assist in accurately locating the plate unit the under face of the outer portion of the translucent element 11 may be beveled as indicated at 24, see particularly Fig. 3, and the upper edge of the side walls of the casing 20 may be similarly 25 beveled as at 25. In this manner the base or casing has an additional centering effect with respect to the plate unit including the translucent means. The extreme outer edge or outer corner portion of the latter desirably is rounded off, 30 as best seen at 26 in Fig. 3. As also best seen in said detail Fig. 3, which is on approximately twice actual scale for my preferred home-plate installation, the exposed face 12 of the translucent means may have a roughened or grid-like formation, 35 comprising a multiplicity of shallow depressions between crossing ribs 21 cast or otherwise formed on the translucent element 11.

In the illustrated example, the plate unit, comprising the parts 7, 9, and 11 and their supporting foot 15 forms in effect a cover or top closure 40 for the casing 20. Within the compartment 21 of the casing I provide one or more light sources 30 illustrated in this instance as of the incandescent bulb form. Three bulbs are here shown, disposed below the front and rear corner portions 45 of the plate unit, in such manner as to transmit light to the translucent element 11 in substantially equally distributed intensity throughout the entire extent of the latter. The number of 50 units and character of the light source may be varied to suit the particular circumstances, and the light or lights may be of other forms than that shown, such as the tubular form, either of the filament or gas-filled type, suitably mounted 55 in the casing 20. The latter is equipped with electric power outlets or connections such as the sockets 31 for the light or lights. Concealed conductors such as indicated at 32, of a waterproof cable, conduit or other type suitable for under- 60 ground installation, connect the light or lights with a convenient power supply, not shown, it being understood that all parts in circuit are adequately insulated and protected from moisture and the elements.

65 The lighting circuit may be arranged to afford remote control for the home-plate illumination, from any convenient station such as represented diagrammatically at S in Fig. 1. Such station may be in or near one of the dugouts, in an official's box in the stands, at some point conveniently accessible to the umpire, or elsewhere as selected. The circuit desirably includes a switch and rheostat or the like as indicated diagrammatically at C in Fig. 1, whereby illumination 70 of the home-plate may be switched on or off 75

as desired, or the degree of illumination afforded may be controlled to suit various playing conditions.

It will be understood that the plate unit with its support 15 may readily be lifted bodily from its installed or operative position, as in Fig. 2, and as quickly reinstalled. At such times when illumination for the home-plate is not desired, the unit accordingly may simply be removed and may be replaced interchangeably by the unit such 10 as illustrated in Fig. 4.

Said latter unit, which may be supplied with and forms a part of my home-plate apparatus as a whole, comprises a similar supporting post 15a depending from and connected to a platform 9a. 15 The plate member proper 7a, of resilient material similar to that of plate 7 as previously described, is of a shape and dimension corresponding to those of said plate 7 and the translucent element 11 together. Thus when placed in operative position with respect to the casing 20 this interchangeable plate 7a will occupy the same space as said two elements of the other unit, thereby presenting a home-plate area of regulation size and shape. 20

The resilient plate member 7a of Fig. 4 may be attached to its supporting platform 9a and the post 15a in any suitable manner. For this purpose I have shown said platform as formed with a number of up-set prongs or flange-like projections 9b, while the post 15a is itself extended upwardly and formed with a top flange 15b. The plate member 7a accordingly may be cast directly on the supporting parts, with the flanges or projections 9b and 15b imbedded in the plate. 30 In some instances a plate unit such as that of Fig. 4 may have its depending support 15a received in a socket in the ground, omitting the casing 20 where illumination is not desired. The plate 7 of the luminous unit may be attached to 40 its supporting platform 9 similarly as just described in connection with the unit of Fig. 4.

From the above it will be apparent that my invention provides means of a simple and efficient character for improving the visibility of 45 game playing areas, and particularly the home-plate of ball fields, so that for players, spectators and umpires alike the traditional difficulty of seeing the plate is largely overcome. The inconvenience and interruption caused by the heretofore frequent necessity for dusting off the plate 50 is avoided, and games may be played or completed under conditions of greater darkness than heretofore practicable, it being particularly noted that the luminous or illuminated plate unit may be installed or removed at any time, even during 55 the progress of a game, with but little interruption in the play, and that the plate lighting may be switched on or off and may be varied in intensity as appropriate to the circumstances. 60

My invention is not limited to the particular embodiment thereof illustrated and described herein, and I set forth its scope in my following claims.

1. A home-plate structure for a baseball diamond, comprising, in combination, a central pentagonal plate-member of resilient material, durable translucent means disposed circumferentially of the plate member along a substantial edge portion thereof and forming with it a structural 65 unit presenting an upper or playing face of regulation home-plate size and shape, and a supporting base for said unit including a chamber for a light source to illuminate said translucent means thereby to define the home-plate area. 70 75

2. A home-plate structure for a baseball diamond, comprising, in combination, a housing adapted to be set in the ground and providing a compartment below the playing level; a plate unit including a resilient plate-forming element, translucent means bordering said element, and supporting means for said plate-forming element and said translucent means, said plate unit adapted for reception and positioning by the housing and providing a top cover for it; and a light source in the compartment in cooperative relation with said translucent means luminously to define the home-plate boundaries.
3. Baseball apparatus, comprising, in combination with a playing field including a diamond; a home-plate element including a main plate member of resilient material, and translucent means outlining said plate member; an underlying rigid support for said element; a housing set substantially flush in the ground at the home-base location and provided with means for removably positioning said plate element and its support; an electric light source in said housing for illuminating said translucent means; and concealed conductor means for controllably connecting the light source with a power supply.
4. A luminously self-definable home-plate structure including a home-plate element having translucent means for at least a substantial border portion thereof and a light source at a level below and operatively associated with said ele-
ment for rendering said translucent means luminous.
5. A home-plate structure comprising a plate element of regulation size and shape and having at least its major central portion of a resilient material, a rigid underlying platform to which said plate element is attached, said platform also supporting translucent means peripherally disposed in the plane of said plate element for luminously defining the home-plate boundaries, and depending means for removably positioning the structure at the home-base location of a baseball diamond.
6. A playing-base structure for baseball and the like, comprising, in combination, a base element presenting a playing area, durable translucent means along a substantial edge portion of said element and forming a structural unit with it, supporting means below the playing level for removably positioning said unit, and a light source associated with said supporting means for illuminating said translucent means thereby to define the base playing area.
7. In a playing-base structure for ball games, in combination, a base element presenting a playing area, a translucent edge formation for said playing area, and means positionable at a level below the playing area to illuminate said formation, the latter being of adequate extent to define luminously the base station.
